UNITED STATES PATENT OFFICE.

ELIAS NASHOLD, OF LOS ANGELES, CALIFORNIA.

FEEDING APPARATUS FOR BOILERS.

No. 862,271.

Specification of Letters Patent.

Patented Aug. 6, 1907.

Application filed January 15, 1906. Serial No. 296,055.

To all whom it may concern:

Be it known that I, ELIAS NASHOLD, a citizen of the United States, residing at Los Angeles, in the county of Los Angeles and State of California, have invented 5 a new and useful Automatic Water-Feeding Apparatus for Boilers, of which the following is a specification.

The invention relates particularly to an apparatus for automatically feeding water into steam boilers and maintaining a definite level in the boiler. The apparatus, however, is capable of other uses, such as feeding 10 oil or water into tanks.

The main object of the invention is to provide an apparatus for the above purpose which will be reliable in operation and which will not be injuriously affected 15 by changes of temperature due to the passage of steam therethrough.

Another object of the invention is to provide an apparatus for this purpose which will be extremely simple and cheap in construction.

20 The accompanying drawings illustrate the invention.

Figure 1 is a side elevation of the apparatus. Fig. 2 is a section on the line x^2-x^2 in Fig. 1. Fig. 3 is a section through the water controlling valve devices. Fig. 4 is a plan of the water connections. Fig. 5 is a 25 section of the steam valve.

1 designates a wall of a boiler or tank and 2 a water pipe, or generally a source of water supply being, for example a service pipe connected to a supply tank. The apparatus constituting the present invention is 30 adapted to feed or transfer the water from said supply into the boiler or tank automatically so as to maintain a definite level in the tank. Said apparatus comprises a rocking frame or beam 3 mounted by trunnions or pivots 4 on a frame or support 5. Said beam may 35 consist of a channel iron fastened by bolts 6 to an axle 7, whose ends are formed as the trunnions 4 turning in bearings 8 on the frame 5. On each end or arm of this rocking beam or lever is mounted a tank 10, each tank being fastened to the beam 3 by a nipple 11 screwing 40 through the beam and communicating into the tank, the respective nipples 11 being connected by pipes 12 with the opposite ends of a valve cylinder 13. A pipe 14 leads from the water supply 2 to the valve means 13. A pipe 15 leads from the valve device to 45 the boiler at or below the water level, and a pipe 16 is connected with the steam space of the boiler and with the respective tanks 10, all of these pipes being flexible so as to permit of the vibratory movement of the apparatus. Steam pipe 16 communicates through a 50 three-way valve 17 into two pipes 18 leading to the respective tanks 10, the said pipes 18 opening into the upper ends of said tanks. The three-way valve 17 is constructed to open connection alternatively to said pipes 18 and is operated automatically by the rocking 55 movement of the apparatus, having an arm 20 con-

nected by a link or rod 21 to a fixed point on the arm 5, so that as the beam rocks, the arm 20 will be swung one way or the other.

The valve means 13 for controlling the water connections consists of a cylinder having two end chambers 22 and an intermediate chamber 23, said intermediate chamber being connected by a pipe 24 to the water supply 14 aforesaid, and each end chamber 22 having a connection by a pipe 12 to one of the tanks 10, and a connection by a pipe 25 including a check valve 25' 65 to the water outlet pipe 15 leading to the boiler. A valve or closure member 26 is pivotally mounted in each chamber 22 to move into and out of closure relation with the openings of outlet pipes 25. Inlet ports 27 are provided in the walls between the inner and outer chambers 23, 22, said inlet ports being also controlled by the said valves 26, to enable the valve member 26 to accommodate itself to the seats of the inlet and outlet ports. Said valve is carried by and pivoted on an arm 28 carried by a rock shaft 29, journaled 70 in and extending through a gasket or stuffing-box 29' in the walls of the valve cylinder 13. The connection or bearing of the valve in this arm, by a pin 30, is sufficiently loose to enable the valve to have a limited free movement in conforming to its seat. Rock shaft 75 29 carries exteriorly of the valve cylinder an operating arm 31, the respective operating arms 31 being connected by screw links 32 with a block or head 33 adjustably connected with a bar 34, pivoted at 34' on a lever 35, pivoted at 35' to the frame 5. On the part 80 connected to the rocking beam, for example, on the axle 7, are fixed two projections, lugs or arms 36, 37 engaging respectively in notches in the upper ends of the bar 34 and the lever 35 to cause a compound lever action in the rocking of said apparatus. 90

Means are provided for holding the rocking frame from accidental or premature movement, so that positive operation thereof will be insured due to accumulation of a definite amount of water. Such means consists of an arm 38 pivoted at 38' to the beam 3 and having shoulders or recessed portions 39 engaging over or under a cross bar 40 on the fixed frame 5. There is a bar 40 at each end of the frame, said bar serving as a stop for the frame in its rocking movement. A weight 41 is adjustably mounted on this retaining arm as by 95 screwing in or out on a screw stud 42 on said arm to adjust the pressure with which the arm bears on the pin aforesaid.

In the above described apparatus, each tank as it empties into the boiler becomes filled with steam from 100 the boiler, and in the reverse direction as the water flows into the tank to fill the same, it displaces the steam, and means are provided to allow of escape of the steam, said means consisting of a float valve in the top of the tank, a plug 45 being screwed into the tank 110

and having a bore in which slides a slide valve 46 having a longitudinal slot or passage 47 communicating with the outer air, the lower end of this slide valve having a float 49 attached thereto so that when the water rises it will elevate the valve to bring a shoulder thereon in contact with a seat in the plug. The valve and float are of sufficient weight to insure the opening of the valve in the reverse operation of the device.

The operation of the apparatus is as follows:—Assuming that the apparatus is in the position shown in Fig. 1 the lever devices 34, 35 hold the water valves in the position shown in Fig. 3 so that communication is established from the supply pipe 2 through pipes 14 and 24 to the intermediate chamber 23 and thence through the port 27 into the left hand chamber 22 which is in communication through one of the pipes 12 with the left hand tank 10, this being the uppermost tank at that time. The valve 26 of the other chamber 22 closes the port 27 to said chamber and opens the outlet port to the pipe 25 leading through a check valve 25' to the outlet pipe 15 in communication with the boiler. The steam valve 17 is in the position shown in Fig. 5, establishing communication from steam pipe 16 through said valve to the pipe 18 leading to the top of the right hand tank 10, said tank 10 being thus in communication with the boiler, both above and below the water level; the level of the water in said tank will therefore be the same as that in the boiler. The water supply being turned on at the service pipe 2, the water will flow through the pipes 14 and 24, intermediate chamber 23, port 27, chamber 22, pipe 12 and nipple 11 to the left hand tank 10, the float valve 46 being at that time in open position so as to allow escape of air or steam in the upper part of the tank as it is displaced by the water. This will continue until the tank 10 is filled, whereupon the float valve will be raised by the float 49 and will close the vent from the tank, whereupon the flow of water will cease. As the water in the boiler evaporates, the water level is correspondingly lowered and the water runs from the right hand tank 10, the water level falling in said tank in correspondence with that in the boiler. Finally, when the right hand tank 10, is about empty, the full tank at the left hand side will overbalance the same, this action being retarded as much as desirable by the action of the retaining or holding device 38, 40. This overbalancing of the rocking frame will operate through the link 21 to throw the steam valve to cut off steam communication to the right hand tank and establish communication to the left hand tank, which then becomes the lowermost tank. At the same time the lugs 36, 37 on the rocking frame act on the lever 35 and bar 34 to throw the operating arms 29 of the valve operating rock shafts by compound lever action so as to move the right hand valve to position to close the outlet and open the inlet port to the right hand chamber 22 and to close the inlet and outlet port to the left hand chamber 22, thus reversing the water connections and putting the left hand tank, which now becomes the lower tank, in communication with the boiler, both above and below the water level. As each tank fills and steam is admitted to the top thereof, the steam pressure will hold the float valve or vent closed, but when the frame overbalances and the tank rises, the steam is cut off and the float valve falls by its own weight, the jar due

to the rocking beam or frame striking the stop bars 40, insuring that the valve will free itself from its seat. The check valves 25' in pipes 25 prevent the back pressure from the boiler from reaching to the valves in the device 13.

70

What I claim is:—

1. In a water feeding apparatus for steam boilers, a rocking frame, a fixed support therefor, tanks carried by said frame, a valve having a water supply connection, an outlet and inlet connection to each tank, and an outlet connection to the boiler, means for automatically operating said valve by the rocking of the frame, a steam pipe connected to the boiler, a three-way valve connected to said pipe and to the tanks, and a link connected to a fixed support and to the three-way valve to operate the latter in the rocking movement of the frame.

75

2. In a water feeding apparatus, a rocking frame, a fixed support therefor, tanks carried by said rocking frame, water supply and outlet pipes, and a valve means connected to said pipes comprising an inlet chamber connected to the supply pipe, two valve chambers having inlet ports communicating with the inlet chamber, and having outlet communications provided with check valves, a rocking valve in each chamber movable to close either the inlet or the outlet port thereof, a pipe leading from each of said valve chambers to one of the tanks, and means for automatically operating the valves in the rocking movement of the frame.

85

3. In a water feeding apparatus, a rocking frame, a fixed support therefor, tanks carried by said rocking frame, water supply and outlet pipes, and a valve means connected to said pipes comprising an inlet chamber connected to the supply pipe, two valve chambers having inlet ports communicating with the inlet chamber, and having outlet communications provided with check valves, a rocking valve in each chamber movable to close either the inlet or the outlet port thereof, a pipe leading from each of said valve chambers to one of the tanks, and means for automatically operating the valves in the rocking movement of the frame comprising a lever pivoted to the fixed support, 95 a bar pivoted to said lever, means on the rocking frame engaging said lever and bar and means connecting the bar to the respective valves aforesaid.

100

4. In a water feeding apparatus, a rocking frame, a fixed support therefor, tanks carried by said rocking frame, water supply and outlet pipes, and a valve means connected to said pipes comprising an inlet chamber connected to the supply pipe, two valve chambers having inlet ports communicating with the inlet chambers, and having outlet communications provided with check valves, a rocking valve in each chamber movable to close either the inlet or the outlet port thereof, a pipe leading from each of said valve chambers to one of the tanks, and means for automatically operating the valves in the rocking movement of the frame comprising lever means operated by said rocking frame, and adjustable connections between said lever means and the said valves.

105

5. In a water feeding apparatus, a rocking frame, a fixed support therefor, tanks carried by said rocking frame, water supply and outlet pipes, and a valve means connected to said pipes comprising an inlet chamber connected to the supply pipe, two valve chambers having inlet ports communicating with the inlet chamber, and having outlet communications provided with check valves, a rocking valve in each chamber movable to close either the inlet or the outlet port thereof, a pipe leading from each of said valve chambers to one of the tanks, and means for automatically operating the valves in the rocking movement of the frame, a pivoted valve carrying arms on which the valve is loosely mounted to adapt itself to the seats of the inlet and outlet.

115

6. In combination with a steam boiler, an automatic water feeding apparatus therefor comprising a rocking frame, a fixed support on which said frame rocks, two tanks supported thereon, on opposite sides of the rocking bearing thereof, a steam pipe connected to the boiler, and a valve controlling communication therefrom alternately to the respective tanks, a water supply pipe, valve means con-

120

125

130

135

140

nected thereto, an outlet pipe leading from said valve means to the boiler, and a pipe leading from said valve means to each tank and operating both as an inlet and as an outlet pipe for the tank, the said valve means establishing communication alternatively to the said pipes from the water supply and from the outlet to the boiler, and means for operating said valves automatically on rocking movement of the frame, an arm pivoted to the rocking frame and having shoulders, and fixed means for engaging said shoulders to frictionally retain the rocking frame from

movement until a certain weight of water accumulates in the tank and a weight adjustably connected to said arm to adjust the pressure with which the frame engages with said fixed retaining means.

In testimony whereof, I have hereunto set my hand at 15
Los Angeles, California, this 6th day of January, 1906.

ELIAS NASHOLD.
